UNITED STATES PATENT OFFICE.

DOMENICO MOMO, OF SALUGGIA, ITALY.

COMBINED WINDOW-RAILING AND FIRE-LADDER.

1,072,024.

Specification of Letters Patent.

Patented Sept. 2, 1913.

Application filed February 19, 1912. Serial No. 678,458.

To all whom it may concern:

Be it known that I, DOMENICO MOMO, a subject of the King of Italy, residing at and whose post-office address is Saluggia, Province of Novara, Italy, postman, have invented certain new and useful Improvements in a Combined Window-Railing and Fire-Ladder, and do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has for its object to provide an escape contrivance in case of a fire or earthquake or other disaster, when, as experience very often has shown, the building staircases become at once unserviceable being pulled down, or too crowded with the many tenants of big houses, or out of reach owing to the fall of the floor between rooms or passages. It is therefore useful to provide in each separate flat and preferably in a room within easy reach and fronting the street, some means for an immediate and easy descent of the people.

This invention has for its object to provide some suitable means for converting the iron railing, now widely adopted in connection with windows extending as low as the floor or near thereto to admit more air and light in the room, into a fire ladder.

This invention is illustrated by way of example in the accompanying drawings.

Figure 1 is an inside front elevation of the railing in the closed position. Fig. 2 is a cross section thereof; Fig. 3 is an outside front elevation of the device in the opened and lowered position in the shape of a ladder; Fig. 4 is a cross section thereof; Fig. 5 is an inside elevation of a modified form of the railing in the closed position; Figs. 6 and 7 are front and side view respectively of the railing shown in Fig. 5 in the opened and lowered position of a ladder. Fig. 8 is a detailed view of the hooking and fastening device for the ladder top according to the modified form of Figs. 5, 6 and 7; Fig. 9 is a plan view of the ladder in its opened position; Fig. 10 is a detailed view of the railing joints. Figs. 11 and 12 are sections on lines $x-x$ and $y-y$ respec-

tively of Fig. 10; Fig. 13 is a front view of a modified form of the railing trellis work in the closed position. Fig. 14 is a similar view in the open position.

The window railing is substantially constituted by a lattice of rails 1 bent to cross each other secured at its upper part to a cross bar 2 either by means of two eyes or hooks 3 sliding along said bar or bolts fixed thereto. To the rails 1 are securely connected the bars 4 serving as ladder steps in the open position. The cross bar 2 slides vertically along two U-shaped guides 5 provided at their lower end with a stop or projection to hold the cross bar 2 and suitably fixed to the wall (Figs. 1 to 4) or to the top rail 6 also of U-shaped section, this latter being either walled in the window jambs (Figs. 1 to 4) or hinged at 7 on one side and bolted at 8 on the other side, (Figs. 5 and 6). A rope 9, preferably of metal, having its lower end secured at 10 at the central part of the lowest step slides in eyes 11 provided at the central joints of the rails 1 and passes over a grooved roller 12 carried by the top rail 6 and is wound upon a drum 13 suitably arranged in a side cavity of one of the jambs. This rope serves as a grasping means for the people descending the ladder and to lift up again the ladder and restore it to the form of a window railing, by operating the drum 13 by means of a crank 14 provided inside the room.

In the constructional form shown at Figs. 1 to 4, the ladder assumes a position parallel with the building front wall; it is therefore necessary to lower it a certain distance from the wall in order to avoid the building lower cornices. For this purpose I provide arms 15 hinged at their lower end to pivot pins 16 while their top end slides in short guides 17 fixed externally to the main guides 5, these latter being for said purpose hinged by their upper end to the pivot pins 18.

In the modified form of Figs. 5 to 8, the ladder is lowered in a position perpendicular to the front wall, the top rail 6 is disengaged from the jamb by taking hold of the inner knob 19, and drawing the bolt 20 with spring 21 out of its hole 8, then the frame is swung out on pivots 7 and the belt forced to enter a similar hole 23 provided in the bracket 22, extending horizontally from the wall. In order to facilitate the stop action in said two holes 8, 23, the bolt 110

may be beveled on two sides as shown in the drawing, but it is preferable to construct it beveled on one side only in order to cause it to enter the hole 23 immediately when being thrown against the bracket; the locking at 8 may always be effected by hand by means of the knob 19. Moreover in order to afford a better support for the weight of the ladder and the people descending it, the bracket 22 may be provided at its outer end with a horizontal projection 24 against which the top rail 6 rests. On said bracket 22 may be placed a lamp 25. Finally in this modified form I arrange on the upper pivot 7 of the top rail 6 a grooved roller 26 over which passes the rope when the railing is thrown outside.

As the weight on the steps 4 could cause the joints of the rails 1 to bend inside thus deforming the ladder and rendering difficult the descent, it will be preferred to provide said rails 1 (or at least some of them at regular intervals) for instance the rail 1^a with an outer tail 1^b to prevent the head of the next rail 1^c to become displaced toward the interior Figs. 10, 11, and 12.

In Figs. 13, 14 is shown a modified form of the jointed lattice work constituting in Fig. 13 a window railing and in Fig. 14 an escape ladder. This form may evidently be used either in the case of Figs. 1 to 4 in which the ladder takes a position parallel with the wall or when the ladder (Figs. 5 to 7) assumes a position at right angles to the wall.

The metallic rope 9 already described allows to regulate the aperture of the railing and therefore the length of the ladder

and also to lift again this latter and restore it to the form of a window railing.

In all the constructional forms above described it will be convenient to arrange the grooved roller at the central part of the cross bar 2 for bending the rope in the vertical direction.

The operation of the device will be clearly understood from the above description and drawings. It will be seen that further modifications may be made without departing from the principle of the invention, consisting substantially in a metallic jointed window railing that may be easily converted into an escape ladder.

What I claim is:

A fire escape having a frame, a trellis-work ladder and hoisting means for the ladder; said frame comprising a top rail between the jambs in the wall, a cross bar from which said ladder is suspended, a pair of vertical guides for said cross bar, horizontal pivot pins in the jambs supporting said vertical guides and a pair of links hinged in the jambs and constructed to slide on said guides, whereby said frame and ladder may be swung out from the house wall and locked in this position so that the ladder will hang free from the wall when let down by said hoisting means.

The foregoing specification signed at Turin, Italy this 29th day of January, 1912.

DOMENICO MOMO.

In presence of—

ITALO BERTOGLIO,
JOCELYN GOUBEYRAN.
